UNITED STATES PATENT OFFICE.

AUGUST SUNDH, OF HASTINGS-UPON-HUDSON, NEW YORK, ASSIGNOR TO SUNDH ENGINEERING AND MACHINE COMPANY, OF PHILADELPHIA, PENNSYLVANIA, A CORPORATION OF PENNSYLVANIA.

APPARATUS FOR TREATING METAL STRIPS.

1,349,444.

Specification of Letters Patent. Patented Aug. 10, 1920.

Application filed December 26, 1919. Serial No. 347,442.

To all whom it may concern:

Be it known that I, AUGUST SUNDH, a citizen of the United States, and a resident of Hastings-upon-Hudson, county of West-
5 chester, State of New York, have invented certain new and useful Improvements in Apparatus for Treating Metal Strips, of which the following is a specification.

My invention relates to a method and apparatus for treating metal strips and particularly to the treating of metal strips preparatory to the pickling operation.

As is well known in the art of manufacturing sheet metal, the metal, as it comes from the rolling mill, is wound up into coils and thereafter placed into ovens to be annealed. After the annealing operation the metal coil is immersed in a vat of acid or other suitable material for the pickling operation, the purpose of the pickling operation being to loosen and remove the scale and dirt with which the metal is coated. As the metal comes from the rolling mill it is wound in a tight coil by power-operated means so that when the coil is placed in the pickling vat the acid or other pickling medium is unable to penetrate between the wraps of the metal coil with the result that the metal will be only imperfectly cleaned.

20 In some instances it is customary to loosen the wraps of the coils by hand before the pickling operation which consumes a great deal of time and the results obtained even then are more or less unsatisfactory.

30 The present invention is directed to a method and apparatus for treating a strip of metal whereby, although the metal is wound in a coil by power-operated means, the wraps of the coil will be slightly spaced or separated so that when the coil is immersed in the pickling bath, the latter will have access to all parts of the metal and thoroughly clean the same throughout its length.

35 Briefly, I have provided an extremely simple apparatus comprising two coil-receiving members, one of which is power driven and the other of which is adapted to receive the coil of metal as the same comes from the annealing oven. The power-driven receiving member is adapted to unwind the coil of metal from the other receiving member and

40 rewind or coil it, a removable separator or spacer being interposed between the wraps of the coil during the rewinding operation. 55 After the metal coil is completely rewound the separator is readily removed and the metal remains in a coiled-up condition with the wraps of the coil slightly spaced or separated from each other so that when the coil 60 is deposited in the pickling bath the latter has access to the metal throughout its length to thoroughly clean the same. As mentioned above, the apparatus involved is extremely simple to construct and operate and 65 the time consumed in the rewinding operation is very short, compared with the old hand method, and much more effective in that the coils of metal in the practice of the present method are positively separated. 70

In the accompanying drawings,—

Figure 1 shows in sectional elevation an embodiment of my invention;

Fig. 2 is a plan view of the apparatus of Fig. 1;

Fig. 3 is a view taken on the line A—A of Fig. 1;

Fig. 4 is a front elevation of the lower part of the apparatus shown in Fig. 1; and

Fig. 5 is an enlarged view of a guide for 80 the removable separator.

Referring now to the drawings in detail, 1 designates a base carrying a hollow column 2 secured thereto in any suitable manner, the column receiving a vertically extending 85 shaft 3 mounted on roller bearings 4 and 5. At the upper end of the shaft 3 and rigidly secured thereto is a metal coil-receiving member 6 adapted to rotate within a member 7 secured to the upper end of the column 90 2, the member 7 having vertically extending flanges 8 and 9, the tops of which are flush with the upper surface of the member 6. The upper end of the shaft 3 extends a short distance above the upper face of the coil-receiving member and is provided with a slot or other suitable means adapted to receive the inner end 10 of a metal coil when the same is transferred from the annealing oven to the coil-receiving member. 95

To one side of the apparatus just described, I have provided a base 11 carrying a vertically extending column 12 within which is mounted a shaft 13, this shaft being

mounted on roller bearings 14 and 15 at each end of the column. The upper end of the column has a laterally extending flange 16 to which is secured a hollow member 17 having a laterally extending flange 18 and vertically extending flange 19, the latter abutting the flange 9 of the member 7, already referred to, when the apparatus is assembled.

Carried by the shaft 13 is a stub shaft 20 mounted on roller bearings 21. Mounted on this stub shaft and keyed thereto is a gear 22 within the casing formed by the flange 16 of the column 12 and the member 17, already referred to. Immediately above the gear 22 and rigidly secured to the stub shaft 20 is a metal coil-receiving member 23, the upper face of which is flush with the top of the flange 18, the upper face of the member 7 and the upper face of the coil-receiving member 6. The upper end of the stub shaft 20 extends a short distance above the face of the coil-receiving member 23 in order that means may be provided about which the metal being unwound from the coil-receiving member 6 may be rewound upon the member 23.

At the lower end of the shaft 13 is mounted a clutch member or disk 24. Also carried adjacent the lower end of the shaft 13 is a gear 25 meshing with a gear 26, the latter being mounted on a vertically extending shaft 27 extending through the flange 16 of the column 12 and carrying on its upper end a gear 28, this gear meshing with the gear 22 already referred to. The gears 25 and 26 and the clutch member 24 are all inclosed within the casing formed by the base 11 and the base of the column 12.

At the side of the casing 11 and secured thereto in any suitable manner I provide means for receiving a removable separator, this means comprising a casting 29 carrying a shaft 30 on one end of which is mounted a driving pulley 31 and on the other end of which is mounted a spool 32 for receiving a removable separator 33 which may be a rope, cord, or other suitable material.

At the side of the casing, as viewed in Fig. 1, I provide an electric motor 34, this motor carrying a gear 35 on its armature shaft, which gear meshes with a gear 36 carried on a shaft 37 extending through the base 11, which shaft carries at its end opposite to the gear 36 a friction pulley 38 adapted to be placed in driving connection with the driving pulley 31 for the separator through the medium of a friction pulley 39 carried by a link 40 secured to one arm of a bell crank lever 41. The bell crank lever 41 constitutes a clutch operating device for the separator 33 and is adapted to be rocked about its pivot 42 by a pedal 43, whereby the pulley 39 will be moved into position to simultaneously engage the peripheries of the friction pulleys 38 and 31.

Mounted on the shaft 37 intermediate the gear 36 and pulley 38 is a sleeve 44, this sleeve carrying at the left-hand end thereof, as viewed in Fig. 1, a pulley 45 and at the other end or at least operatively connected to the other end, a pulley 46. The sleeve 44 is adapted to be moved longitudinally of the shaft 37 by means of levers 47 and 48, the lever 47 being secured to the sleeve 44 in any suitable manner and being pivoted to the lever 48, the latter being pivoted at 49 and having an extension 50 to the exterior of the casing 11 whereby the same may be foot-operated to cause the sleeve 44 to be moved longitudinally of the shaft 37, either to the right or left, as the case may be, to bring the pulley 45 or the pulley 46 into driving engagement with the face of the clutch member 24.

In operation a coil of metal 51 from the annealing oven is placed upon the metal receiving member 6, the inner end 10 of the coil being inserted in the slot provided for that purpose at the upper end of the shaft 3 or connected to the member 6 in any other suitable manner. The outer end 52 of the coil is then led over to the member 23 and secured to the extension 53 of the stub shaft 20 provided for that purpose, where the end of the coil is secured in any suitable manner as by inserting it in a slot provided therein. The removable separator 33 is then led up over a pulley 54 mounted in the flange 18 and over to the end 52 of the metal strip. The controlling lever 50 is then operated to bring either the clutch member 45 or 46 into engagement with the clutch member 24 depending upon which direction it is desired to coil the metal, and assuming that the motor 34 has already been set in motion, movement of the pulley 46 or 45, as the case may be, into engagement with the clutch 24 will cause the gear 25 to rotate, which in turn, will drive the gear 22 connected directly to the coil-receiving member 23 through the medium of gears 26 and 28. The spool 32 carrying the separator 33 is at this time running free and as the coil receiving member 23 is rotated, as just described, the metal will be unwound from the coil upon the metal receiving member 6 and rewound upon the member 23 with the separator 33 interposed between the wraps of the coil.

After the metal has all been transferred from the member 6 to the member 23, the latter is brought to rest. The separator 33 is then placed in a guide slot 55 in a guide member 56 of glass or other suitable material, said member being supported by an arm 57 secured to the member 17, the guide member being located substantially in line with the axis of rotation of the coil-receiving member 23.

The foot pedal 43 is then depressed to 130

bring the clutch member or pulley 39 into simultaneous engagement with the clutch member 38 and pulley 31. The motor 34 being in motion will then drive the spool 32 carrying the separator 33 to pull the separator from between the wraps of the metal coil on the member 23 and rewind it upon the spool 32, leaving the wraps of said coil separated from each other.

10 If the coil now be placed in a pickling bath it will be seen that the pickle has free access to the coil of metal throughout its entire length.

It will be apparent from the foregoing 15 that I have provided a very simple and inexpensive apparatus whereby a coil of metal may be wound up under power and yet have the wraps of the coil separated or spaced from each other for the purpose set forth.

20 It will be apparent also that the time required to rewind the coil with the separator between the wraps of the metal is very short and that the method as a whole is much more satisfactory than the old hand methods herein referred to.

It will be apparent also that if desired the speed of rotation of the coil receiving member 23 may be varied as desired, to shorten or lengthen the time required for the coiling 30 operation by merely moving the pulley 45 or 46, as the case may be, toward or away from the axis of rotation of the clutch member 24. It will be obvious, furthermore, that the direction of rotation of the coil receiving member 23 is optional as the pulleys 45 and 46 will drive the clutch member in either direction, depending upon which of these pulleys is clutched in; also if it be desired to stop the coil receiving member 23 35 quickly, this can be done by merely operating the clutch lever 50 to throw out one clutch and throw in the reverse.

It is to be understood that the apparatus herein described is merely illustrative, and 40 that changes therein may be made within the purview of this invention.

What I claim as new is:

1. In a metal-coiling apparatus of the 50 class described, the combination of a coil-receiving member, a separator for separating the wraps of a metal coil coiled upon said receiving member, and means for removing said separator to leave the metal coiled upon the receiving member with the wraps thereof spaced from each other.

2. In a metal coiling apparatus, the combination of a separator for separating or spacing the wraps of a coil of metal, and means for removing said separator while 60 the metal is in a coiled up condition to leave the wraps of the metal coil separated from each other.

3. In an apparatus of the class described, the combination of a coil-receiving member, 65 a removable separator, means for actuating

said coil-receiving member to wind a coil of metal on the same with said separator interposed between the wraps thereof, and means for removing said separator to leave the metal coiled up with the wraps thereof 70 separated or spaced from each other.

4. In an apparatus of the class described, the combination of a plurality of metal coil-receiving members, a removable separator, means for unwinding the metal coil from 75 one of said coil-receiving members and rewinding the same upon another of said members with the separator interposed between the wraps of the metal, and power-operated means for removing the separator from the coil to leave the wraps of the metal coil separated from each other.

5. In an apparatus for treating metal, the combination of a metal coil-receiving member, a separator, a power-driven metal coil-receiving member for winding the metal from the first-named receiving member into a coil with the separator interposed between the wraps thereof, and means for removing the separator to leave the 80 metal in a coiled-up condition with the wraps thereof spaced from each other.

6. In an apparatus of the class described, the combination of a metal coil-receiving member, a separator, means for receiving 85 said separator, driving means for said metal coil-receiving member to cause a strip of metal to be coiled thereon with the separator interposed between the wraps of the metal, the receiving element for the separator being operable independently of the driving means for the metal coil-receiving member.

7. In an apparatus of the class described, the combination of a coil-receiving member, a removable separator, means for actuating 100 said coil-receiving member to wind a metal strip in a coil upon said member with the separator interposed between the wraps thereof, power-operated means for actuating said coil-receiving member in winding the metal and for removing the separator from said coil while the metal remains in a coiled-up condition.

8. In an apparatus of the class described, the combination of a coil-receiving member, a removable separator, means for rotating 110 said coil-receiving member to coil a length of metal upon the same with said separator interposed between the wraps of the coil, a receiver for the separator, and guiding means for said separator for guiding the same as the separator is drawn from between the wraps of the coil of metal and wound upon its receiver.

9. In an apparatus of the class described, the combination of a coil-receiving member mounted upon antifriction bearings and having means for securing one end of a metal coil thereto, a coil-receiving member 120

having means for securing the other end of a metal coil thereto, a separator, driving means for said last-named coil-receiving member to unwind a coil of metal from the 5 first-named coil-receiving member and rewind it upon the second-named coil-receiving member with the separator interposed

between the wraps thereof, said driving means comprising a motor and a variable speed reversible clutch for connecting said 10 motor to said coil-receiving member.

This specification signed this 24th day of December, 1919.

AUGUST SUNDH.
